Inventor
Andrew Thoma
by Charles W. McDerrow
His Atty.

UNITED STATES PATENT OFFICE.

ANDREW THOMA, OF CAMBRIDGE, MASSACHUSETTS, ASSIGNOR TO ABRAHAM SYDEMAN, OF BOSTON, MASSACHUSETTS.

DOUBLING SPREADER.

Application filed July 15, 1918. Serial No. 244,848.

To all whom it may concern:

Be it known that I, ANDREW THOMA, a citizen of the United States, residing at Cambridge, in the county of Middlesex and 5 State of Massachusetts, have invented certain Improvements in Doubling Spreaders, of which the following description, in connection with the accompanying drawings, is a specification, like reference characters 10 on the drawings indicating like parts in the several figures.

This invention relates to a method and apparatus of the type which are designed to apply a coating of rubber compound or 15 other adhesive to one face of a web of fibrous or textile material and then to apply a second web to the coated face of the first web thereby producing a two-ply web or double texture fabric.

20 The general object of the invention is to provide a novel construction and a novel method by means of which the webs of material are more smoothly and intimately associated and the adhesive spread more evenly 25 between them, the spreading taking place along the line where the two webs are doubled together.

The method is carried out by, and the construction effected in, the preferred embodiment of the invention illustrated herein by employing a doubling bar across which the two webs pass from different directions, said bar having a salient web engaging surface arranged to engage the central portion of 35 the webs at a point in advance of that at which it engages the edge of the webs, said bar acting to stretch the webs laterally in each direction from the central portion and to effect an even pressure along the line at 40 which the two webs come in contact, and in cases where the character of the coating means permits, also an even spreading of the coating along the same lines. By the term salient web engaging face it is to be 45 understood that the web engaging face may be bowed or may be formed to present straight lines diverging from the central portion or apex in the direction of feed and that while the advance portion of the bar 50 preferably is at the center it may be arranged at either side of the center to perform the function above described, within the spirit and scope of the invention covered by the annexed claims.

In order to impart an understanding of 55 the invention, I have illustrated in the drawings a selected embodiment of a machine embodying the invention which will now be described, after which the novel features of the method and apparatus will be pointed 60 out in the appended claims.

In the drawings:

Fig. 1 is a side view of a machine embodying my invention; and

Fig. 2 is a plan of the doubling bar. 65

The machine herein shown comprises a suitable frame 1 on which is mounted two reels or drums 2 and 3 from which are drawn the webs 4 and 5 to be doubled together. One and usually both of these webs are in 70 practice generally already coated on the faces to be brought together with a suitable adhesive and generally waterproof coating.

The web 4 is shown as passing through a coating device, indicated generally at 6, by 75 which a coating of rubber or adhesive compound is applied to one face of the web and this coating secures the final adhesion of the two webs. This coating device may have any suitable or usual construction. It is 80 herein illustrated as comprising a roll 7 over which the web passes, and a spreading knife 8 situated directly above the fabric and by which the adhesive material is spread on the fabric, said material being located 85 behind the knife, as shown at 9. The knife is secured to a carrier 10 which is vertically adjustable in ways 11 by means of the adjusting screw 12, thereby providing for applying a coating of any desired thickness. 90

From the coating device 6, the web 4 passes over a guide roll 120, thence under a doubling bar 13, at which point the web 5 is applied to the web 4, both webs passing across the spreader bar together. From the doubling bar the two superposed webs pass over the guide roll 14 and then around a steam heated drum 15 which is journaled in the frame at 16. From the drum the combined webs pass to a drum or reel 17 on which 100 they are wound. The purpose of the steam heated drum 15 is to dry the coating and cause it to set. The drum 17 will preferably be positively driven so as to draw the webs through the machine. 105

The doubling bar 13 is of novel construction and is designed to effect an even pressure on the webs or an even spreading of the coat-

ing of adhesive material along the line where the two webs 4 and 5 are doubled together. This bar is shown as journaled in blocks 18 mounted in ways 19 and capable of adjustment in the ways by means of adjusting screws 20. The bar 13 has a salient web-engaging portion, that is, said bar is constructed so that the portion thereof over which the webs pass will have engagement 10 with the central portion of the webs at a point in advance of that at which it engages the sides of the webs. The bar herein shown is constructed so that the web-engaging portion thereof each side of the central point 21 of the bar inclines slightly in the direction of the feeding movement. The doubling bar 13 is so situated that as the webs are drawn thereacross, the central point 21 of the bar will engage the web at a point in advance of 20 that at which the ends 22 have engagement with the web. The result will be that each half of the bar will be acting on the web along a line inclined to a line extending transversely of the web.

25 The web 4 of the fabric preferably is bent abruptly downwardly beneath the doubling bar as illustrated in Fig. 1 and the web 5 led from the roll 3 around the doubling bar into contact with the web 4. By reason of this 30 construction a considerably greater stress is placed upon the central portion of the web than upon its edges, the stress decreasing gradually from the center to the edges of the superimposed web.

35 By reason of this construction a lateral spreading or tension is applied transversely of the web of cloth and by reason of the divergence of the web-engaging surface of the bar from its central portion an even pressure 40 on the webs is exerted to stick them together. This construction of the bar when the character of the coating permits, progressively forces the coating laterally and more evenly 45 distributes the coating from the center toward the edges as the webs are drawn beneath the doubling bar, thus inserting an even spreading of the coating.

50 The doubling bar is adjustably mounted in the blocks 18 so that it can be turned therein about its axis thereby to move the angular web-engaging edge 23 into different angular positions relative to the direction of movement of the webs. This adjustment is effected by providing the bar with an arm or 55 handle 24 which is rigidly secured thereto and by which it may be turned. The handle is provided with a holding pin adapted to snap into any one of a plurality of notches 25 formed in the frame, thus holding the bar in adjusted position.

Any suitable winding mechanism may be provided to draw the webs around the drum 15 and wind the same upon the reels 17 and the drums 2 and 3 may be provided with a 60 suitable brake mechanism 26 for applying

the desired tension to the respective webs 4 and 5.

I believe I am the first to form double texture fabric by applying an adhesive coating to one or both of the faces to be brought together and by thus progressively bringing said webs into juxtaposition and applying pressure, preferably a dragging pressure on lines inclined from the central portion of the webs toward the edges thereof and thus effecting an evening and smoothing of the webs and of the intermediate coating from the center toward the edges, whether or not the coating means employed is capable of flowing laterally under the doubling pressure.

It is to be understood that the embodiment of the invention disclosed herein is of illustrative character and is not restrictive and that various modifications may be made within the spirit and scope of the following claims.

Having thus described my invention which I claim as new and desire to secure by Letters Patent is:

1. A doubling spreader, having, in combination, means for supporting a web, means for coating one face thereof, means for progressively superposing another web on the coated face of the first web, and means acting through one of the webs for exerting an evening and smoothing pressure in the direction of the feed of the web upon said webs and said coating along the line where the two webs are doubled together. 100

2. A doubling spreader, having, in combination, means for supporting a web, means for coating one face thereof, means for progressively superposing another web on the coated face of the first web, and means acting through one of the webs on a line inclined to the direction of feed to exert an evening and smoothing pressure upon said webs and the coating. 105

3. A doubling spreader, having, in combination means for feeding a web, means for coating one face thereof, means for applying a second web to the coated face of the first web, and a doubling bar across which said webs pass at the point where they are doubled together, said bar being arranged to cause each web to be deflected as it passes thereacross, the portion of the bar with which the doubled web contacts being shaped to engage the web on a line inclined to the direction 115 of feed. 120

4. A doubling spreader, having, in combination, means for feeding a web, means for coating one face thereof, means for applying a second web to the coated face of the first web, and a doubling bar across which said webs pass at the point where they are doubled together, said bar being situated to cause each web to be deflected as it passes thereacross, and the portion of the bar with 125 130

which the doubled web contacts being shaped to engage the web on a line inclined to the direction of feed from the central part of the bar toward each edge of the web.

5. A doubling spreader, having, in combination, means for coating a web, means for progressively superposing another web on the coated face of the first web, and means for applying pressure to said webs on lines 10 inclined from the central portion of the web toward the edges thereof and extending in the direction of feed of the webs.

6. A doubling spreader, having, in combination, means for feeding a web, means for 15 coating one face thereof, means for applying a second web to the coated face of the first web, a spreader bar engaging the superposed web and situated in such a position as to cause the webs to be deflected abruptly 20 downwardly as they pass therebeneath, the portion of the spreader bar engaging the web having a salient to engage the web on a line inclined in the direction of feed from the central portion of the web to the edges 25 thereof.

7. A doubling spreader, having, in combination, a doubling bar having a salient web-engaging face, means for feeding two webs across said face from different angles, and

means for coating one web in advance of 30 said spreader bar.

8. A doubling spreader, having, in combination, means for supporting a web, means for coating the web, means for progressively superposing another web of coated material 35 on the first web, and means for applying pressure upon said webs along a line diverging from the central portion of the web toward the edges thereof in the direction of feed whereby a lateral spreading of the 40 webs is effected and an even distribution of the coating intermediate of said webs is secured.

9. A machine for doubling coated webs, having, in combination, a doubling bar having 45 a web-engaging face, means for feeding two webs across said face, and means for varying the angular position of said face with relation to the direction of movement 50 of the webs.

10. A machine for doubling coated webs, having, in combination, a doubling bar, vertically movable blocks in which the bar is rotatably mounted, and means for locking 55 the bar from rotation.

In testimony whereof I have signed my name to this specification.

ANDREW THOMA.
